BY *Henry A. Matthews*

ATTORNEY

UNITED STATES PATENT OFFICE.

JOSEPH KERENSKY, OF WASHINGTON, DISTRICT OF COLUMBIA.

CONVERTIBLE FURNITURE.

Application filed January 17, 1929. Serial No. 333,177.

My invention relates to improvements in a combined seat element, such as a chair or divan, and bed.

In accordance with my invention, I provide convertible furniture which may be readily used as a chair or divan, and also as a bed. The foldable bed element may be removed as a unit from the chair or divan element. The arrangement of the parts is such that the folding elements of the bed element are all arranged within the chair or divan element, when the furniture is used as a chair or divan. The bed element which is designed to carry a mattress, is so constructed that suitable space is afforded within the chair element, to accommodate the folded mattress. The furniture may be manufactured cheaply and is particularly designed to be constructed of metal tubes or pipes. The frame of the chair or divan and of the mattress element may be covered with wicker or may be otherwise suitably upholstered.

In the accompanying drawings, forming a part of this specification, and in which like numerals are employed to designate like parts, throughout the same,

Figure 1 is a front elevation of the convertible furniture embodying my invention, showing the same used as a chair,

Figure 2 is a side elevation of the same,

Figure 3 is a plan view of the same, showing it used as a bed,

Figure 4 is a side elevation of the same,

Figure 5 is a longitudinal section taken on line 5—5 of Figure 3,

Figure 6 is a fragmentary perspective view of the inner end of the bed bottom of the bed element,

Figure 7 is a vertical sectional view taken on line 7—7 of Figure 1,

Figure 8' is a vertical section taken on line 8'—8' of Figure 5,

Figure 8^a is a detailed section through the link,

Figure 8 is a front elevation of a combined divan and bed,

Figure 9 is a side elevation of the same,

Figure 10 is a plan view of the same, showing the bed element distended,

Figure 11 is a side elevation of the same,

Figure 12 is a longitudinal section taken on line 12—12 of Figure 10,

Figure 13 is a fragmentary perspective

view of the bed bottom included in the bed element,

Figure 14 is a central vertical section through the furniture, showing the bed element collapsed, and,

Figure 15 is a transverse section taken on line 15—15 of Figure 13.

In the drawings, wherein for the purpose of illustration, are shown preferred embodiments of my invention, attention being called to Figures 1 to 8^a, inclusive, the numeral 20 designates a chair element as a whole, comprising an inverted U-shaped back frame 21, preferably formed of bent pipe or tube. The lower portions of this back frame form rear legs 22. The upper portion of the back frame 70 carries a generally inverted U-shaped rod 23, the ends 24 of which are rigidly attached to the back frame by welding or the like. Short intermediate rods 25 serve to connect the rod 23 and the top of the back frame. The arms 75 26 are also preferably formed of tubes or pipes and embody horizontal portions which are welded to the back frame. At their forward ends, these arms are bent downwardly to produce front legs 27. The legs 22 and 27 being tubular, receive the shanks of rollers or casters 28.

The numeral 29 designates diagonal rods or tubes, having their upper ends attached to the back frame 21 by welding or the like, 85 and these rods or tubes are inclined downwardly forwardly and terminate in hooks or U-shaped sockets 30, which are welded to the front legs 27. The numeral 31 designates a bed element as a whole. This bed element is 90 formed in three foldable sections. The outer section embodies side rails 32, connected by a transverse rail 33. The intermediate section embodies side rails 34, connected with the side rails 32 by hinges 35, arranged upon the 95 lower sides of the same. The inner bottom section embodies side rails 36, connected by a transverse rail 37. The inner ends of the side rails 34 are provided with knuckles 38, and these knuckles are arranged between the knuckles 39 of links 40, and are pivotally connected therewith by pins 41. Extensions 42, formed upon the ends of the links 40, serve to limit the swinging movement of the links 40, with relation to the rails 34, as will 100 be described.

The rails 36 are provided at their free ends with knuckles 43, arranged between knuckles

44 of the links 40, and pivotally connected therewith by pins 45. The links carry extensions 46, adapted to engage beneath the rails 36, limiting the downward swinging movement of the rails with relation to the links, under certain conditions. Hinge leaves 47 are rigidly attached to the sides of the rails 34, which are lowermost when the bed element is distended, and these hinge leaves 5 carry knuckles 48, arranged between knuckles 49, carried by hinge leaves 50. These sets of knuckles are pivotally connected by a transverse rod 51, carrying a spacing sleeve 52 and spacing elements or washers 53. The 10 ends of the rod 51 are inserted within the U-shaped sockets 30. The lower ends of the hinge leaves 50 are detachably connected with a metal strap 52', by means of screws 53', or the like. The ends of the metal strap are 15 bent into sockets 54, which surround the front legs 27, and are attached thereto by screws 55, or the like. The numeral 56 designates leaf-springs, which are curved, and have their upper ends attached to the hinge leaves 50, 20 while their lower ends are free. These leaf-springs are arranged in the path of travel of the links 40, during their folding action, and serve to fold the links, with the minimum shocks or jars. The links 40 not only serve 25 as a hinge connection between the rails 34 and the rails 36, but provide means whereby these rails are vertically spaced a substantial distance when folded, to accommodate the folded mattress.

30 The rails 32 are provided with upwardly extending arm covering frames 57, rigidly attached thereto, and adapted to fold over the arms 26. At their forward ends, these arm covering frames are continued in the 35 form of a foot covering frame 58. When the bed element is collapsed, the foot covering frame 58 covers the front feet 27 of the chair element, and when the bed element is distended, the foot covering frame 58 serves to support the forward end of the bed element.

40 The front legs 27 are connected by a transverse tube 27', and the rear legs by a transverse tube 22'. The tubes 27' and 22' are connected by stop rods 28', engaged by the rail 37, when the bed sections are folded. The front and rear legs are connected by tubes 29'.

45 The bed section rails 32, 34 and 36 carry a spring bed bottom 59, and a mattress 60 is arranged upon this spring bed bottom.

50 The frame work of the chair element including the back frame and arms may be covered with wicker or other suitable upholstery. The arm covering frames 57 and the leg covering frames 58 are also adapted to be covered by wicker or other suitable upholstery.

55 When the furniture is used as a bed, the body element is distended to assume a generally horizontal position, as clearly shown

in Figure 5. The foot covering element 58 rests upon the floor and supports the forward end of the bed element. The hinges 35 now prevent rails 32 and 34 swinging downwardly. The links 40 can not now swing 70 downwardly below the horizontal, as their extensions 42 contact with portions of the hinge leaves 47. The rails 36 engage the upper surfaces of the extensions 46, whereby these rails can not swing below the horizontal. The user has his head arranged at the outer end of the bed element, between the arm covering frames 57, whereby the major portion of the weight is carried at the outer end of the bed element. To collapse the bed 75 element, the user raises the rails 32, which will now fold upon the hinges 35 and forces the same toward the chair element. The rails 34 also turn upon the rod 51, whereby rails 32 and 34 become folded in a substantially 80 parallel relation. The inward swinging movement of the rails 34, swing the links 40 within the bottom portion of the chair frame, and these links slidably engage the leaf-springs 46, whereby they properly turn upon 85 their joints. The rails 36 engage the bottom rods of the chair frame and hence the rails 36, properly fold upon the links. The links afford a proper space between the folded rails 34 and 36, to accommodate the double layer of the folded mattress.

90 Attention being called to Figures 8 to 15, inclusive, the numeral 60 designates a chair element, as a whole, embodying an inverted generally U-shaped back frame 61, preferably formed of a tube or pipe. An edge frame 62 is attached to the upper end of the back frame, by welding or the like, and is also connected with transverse tubes or rods 63, welded to the same and to the top of the back 100 frame. The lower portions of the back frame 61 constitute the rear legs 64 of the chair element. The numeral 65 designates arms, formed of pipes or tubes, the rear ends of which are welded to the back frame, and these arms are bent downwardly at their forward ends forming front legs 66. The legs 64 and 66 are tubular and hence receive the shanks of rollers or casters 67. The rear and front legs are connected by transverse 105 pipes or tubes 68, connected with vertical rods 69, attached to the arms 65. The rear legs 64 are connected by upstanding tubes or rods 70, the upper ends of which are attached to the top of the back frame. The front legs 66 110 are connected by a horizontal tube or pipe 71, as shown. The back frame and the frame work provided by the arms 60, pipes 68, and rods 69, may be covered with wicker or other 115 suitable form of upholstery.

120 The bed element is formed in three foldable sections. The forward section includes side rails 72, connected by a transverse rail 73. The intermediate section includes longitudinal rails 74, connected with the rails 72 130

by hinges 75, and these hinges are positioned upon the lower sides of the rails 72 and 74 when the bed element is distended. The inner section includes longitudinal rails 76, connected by a transverse rail 77.

The rails 76 are provided with knuckles 78, arranged between knuckles 79 of links 80, and pivoted thereto by pins 81. The links 80 carry extensions 82, adapted to engage the lower faces of the rails 76, and to prevent the rails 76 from swinging downwardly below the horizontal, as clearly shown in Figure 12. The opposite ends of the links 80 are equipped with knuckles 83, receiving therebetween knuckles 84, carried by the rails 74. These knuckles are pivotally connected by removable bolts 85. The links 80 also carry extensions 86, engaging beneath the rails 74, to prevent the links 80 from swinging downwardly below the horizontal, as clearly shown in Figure 12.

The bolts 85 which are removable, pass through apertured heads 87, carried by uprights 88, which are welded to the front pipe 71. The inner ends of these bolts are screw-threaded for engagement within screw-threaded openings formed in lugs 89, carried by the front legs 66. Stop elements 90 are welded to the uprights 88 and to the front legs, and are arranged in the path of travel of the links 80, to limit their forward movements. A supporting bar or element 90 is arranged beneath the rails 76 and are attached to the longitudinal bars 68. When the several sections of the bed element are collapsed or folded, Figure 14, the links 80 provide sufficient space between the sections 74 and 76 for the reception of the folded mattress.

The rails 72 carry arm covering frames 91, which are adapted to cover the arms 65, and these frames are bent downwardly forming a leg covering frame 92. The leg covering frame 92 is adapted to cover the front legs 66, when the bed element is collapsed, and when it is distended, serves to support the front end of the bed element. The rails 72, 74 and 76 carry a spring bottom 93, of any well known or preferred construction.

In this form of the invention, by removing the bolts 85, the bed element as a unit may be separated from the chair element. When the bed element is distended, as shown in Figure 12, to fold or collapse the same, the rails 72 are raised and shifted rearwardly. These rails turn upon the hinges 75 which raise the rails 74 and swing them rearwardly. The rails 74 turn upon the bolts 85. The upward rearward movement of the rails 74 causes the rails 76 to be lowered until they rest upon the support 90. Further inward movement of the rails 72 and 74 cause the same to be arranged in generally parallel relation above the rails 76. The links 80 afford a

suitable space between the rails 74 and 76 to receive the folded section of the mattress.

It is to be understood that the forms of my invention, herewith shown and described, are to be taken as preferred examples of the same and that various changes in the shape, size and arrangement of parts, may be resorted to without departing from the spirit of my invention, or the scope of the subjoined claims.

Having thus described my invention, I claim:

1. In convertible furniture, a seat element, a foldable bed element embodying pivotally connected rails, a rod pivotally connected with selected rails, and sockets secured to the seat element and removably holding the rod.

2. In convertible furniture, a seat element, a foldable bed element embodying pivoted rails, hinges having upper and lower leaves and a rod, means for attaching the upper leaves to selected rails, means for detachably connecting the lower leaves with the seat element, and sockets secured to the seat element and having their upper ends open and receiving the rod.

3. In convertible furniture, a seat element, a bed element comprising forward and rear rails and intermediate rails, hinges connecting the forward rails and the intermediate rails, links pivotally connected with the intermediate rails and with the rear rails, and means for hinging the intermediate rails to the seat element so that the links swing into the seat element and provide a space between the folded intermediate rails and the rear rails.

4. In convertible furniture, a frame for a chair or divan, a bed element comprising inner and outer rails and intermediate rails, hinges connecting the intermediate and outer rails, links pivotally connecting the inner rails and intermediate rails, a pivot element carried by the forward side of the chair frame and arranged beneath the links, hinges secured to the intermediate rails and mounted upon the pivot element, and a stop arranged in the lower portion of said frame in the path of travel of the inner rails, the arrangement being such that the links are folded into the inner portion of said frame when the intermediate rails are folded over the inner rails.

5. In convertible furniture, a frame for a chair or divan, a bed element comprising inner and outer rails and intermediate rails, hinges connecting the intermediate and outer rails, links pivotally connecting the inner rails and intermediate rails, a pivot element carried by the forward side of said frame and arranged beneath the links, hinges secured to the intermediate rails and mounted upon the pivot element, springs arranged near the pivot element and disposed in the path of travel of said links to engage therewith, and

a stop arranged in the path of travel of the inner rails.

6. In convertible furniture, a frame for a chair or divan, said frame including arms, a foldable bed element connected with said frame, and covering arms carried by the foldable bed element and movable outwardly with the same when the bed element is opened and movable inwardly when the bed element is closed to cover the arms of the frame.

7. In convertible furniture, a frame for a chair or divan, including arms and legs, a

foldable bed element connected with the frame, and covering arms attached to the foldable bed element and extending downwardly to provide a covering leg, the covering arms being arranged over the arms of said frame and the covering leg disposed in advance of the front legs of said frame when the foldable bed element is closed, said covering leg serving to support the free end of the bed element when it is open.

In testimony whereof I affix my signature.

JOSEPH KERENSKY.
